METHOD OF MAKING A BALL FOR BALL POINT PEN

Meuriel F. Reed, St. Louis, Mo., assignor, by mesne assignments, to Paper Mate Manufacturing Company, Culver City, Calif., a corporation of Delaware

Application June 13, 1955, Serial No. 515,120

7 Claims. (Cl. 29—148.4)

The present invention relates generally to ball point pens, and more particularly to an improved method of making a ball for ball point pens which enables the pen to write on glazed, oiled, or similar surfaces having relatively low coefficients of friction.

For many years, until comparatively recently, the difficulty of writing with free-flowing liquid ink upon highly glazed or oiled surfaces was widely recognized as an inherent shortcoming in the writing implement art. A long forward step was made with the development of quick-drying inks having low surface tension and high adsorptive qualities. The use of such inks in split point pens has generally surmounted the fundamental difficulty above noted. In other words, with inks now available, it is only necessary to spread the ink in a satisfactory manner over glazed paper or the like in order to obtain the desired result.

Considering ball point pens, however, the ability to spread ink over a glazed or oiled surface involves more than the employment of a particular type of ink. As is well known, the ink from ball point pens is applied to the paper by rolling a spherical ball over the paper, the ball being coated with a film of ink. Thus, there exists a theoretically nonsliding "printing" engagement between the ball and the paper, as distinguished from the familiar sliding or "brushing" engagement of a split pen point. From its inception, the ball point pen has been notoriously inefficient in use with glazed paper notwithstanding the employment of inks having high adsorption. The reason for this, of course, is that the ball at the tip of the ball point pen tends to slide, rather than to roll, on the glazed surface, the friction between the paper and the ball being insufficient to cause the latter to turn in its socket.

It has now been found that by providing a ball having an especially prepared roughened spherical surface, a coefficient of friction is obtained which is sufficient to enforce rolling contact of the ball even on glazed surfaces. It has also been found that a particular general type of abraded surface is distinctly preferable from the standpoint of the operative life of the tip which retains the ball. The present invention, therefore, teaches a method for roughening the surface of a ball for a ball point pen.

It is a primary object of the invention to provide a method of making a roughened ball for a ball point pen which operates efficiently with glazed, oiled or other smooth ink-receiving surfaces.

It is another object of the invention to provide a ball for ball point pens which has its spherical surface provided with an especially roughened finish for increased coefficient of friction with smooth surfaces.

It is another object of the invention to teach a method for providing a roughened finish on a ball for ball point pens.

The foregoing, along with additional objects and advantages, will be apparent from the following description taken in conjunction with the accompanying drawing, in which:

Figure 1 is a fragmentary cross-sectional view taken

2

on the longitudinal axis of a filler for ball point pens, the filler including a tip assembly having a ball constructed in accordance with the teachings of the present invention;

Figure 2 is an enlarged representation of a ball similar to that of Figure 1, prior to being completely formed;

Figure 3 is an exaggerated cross-sectional representation of a ball similar to that of Figure 2 after an abrading operation; and

Figure 4 is an exaggerated cross-sectional representation of a ball similar to that of Figure 3 after a burnishing or polishing operation.

Referring more particularly to the drawing through the use of reference characters placed thereon, the numeral 10 designates generally a filler for a ball point pen. As is clear from Figure 1, the filler 10 comprises a tip 12 press-fitted into one end of a reservoir tube 14 and provided with a socket 16 for accommodating a spherical ball 18.

The tip 12 has a main longitudinal passage 20 for conducting ink from the reservoir 14 down to the socket 16. A plurality of grooves 22 is provided for insuring distribution of the ink over the interior of the socket 16. As will be observed from Figure 1, the interior dimension or spherical radius of the socket 16 may be somewhat greater than the spherical radius of the ball 18, which leaves a gap or space 24 between the surface of the ball 18 and the surface of the socket 16, and thus provides a shell-like passage into which ink may emerge from the lower end of the passage 20 and grooves 22. Such a film of ink between the socket 16 and the ball 18 eliminates actual surface engagement between these elements, and thus serves as a liquid lubricant. The extreme lower end of the socket 16 is formed by an annular edge 26 which, as is well understood in the art, is spun inwardly so as to retain the ball 18 within the socket.

Figure 2 depicts a ball 28 having a smooth polished spherical surface 30, as is conventional in respect to balls used for ball point pens. This type of ball, used in ball point pens since their inception, has performed with general satisfaction except when used upon glazed or oiled surfaces. In these latter instances, the coefficient of friction between the smooth surface 30 of the ball 28 and the particular glazed or oily surface has been insufficient to cause the ball to rotate in a manner to deposit ink on such surfaces.

The illustration of Figure 3 shows a ball 32 provided with a roughened surface 34 formed by lapping the smooth spherical surface 30 of a ball 28 with an abrasive dust. A satisfactory abraded surface 34 has been obtained with the use of flowered corundum powder of approximately 700 mesh in an oil vehicle. The lapping operation may comprise rolling the ball between two hard surfaces charged with the abrasive substance.

It may be mentioned at this point that a ball 32 provided with an abraded surface 34 could be employed in the tip 12, and would perform with fair efficiency upon smooth glazed ink-receiving surfaces. Experience has demonstrated, however, that the surface 34 has minute radial projections which penetrate the lubricating film of ink and rasp the interior surface of the socket 16 to an extent that the latter quickly becomes worn to such an extent that the ball 18 may be completely received in the socket 16. Obviously, under such a condition, the filler 10 ceases to operate.

Figure 4 illustrates a ball 36 provided with an indented surface 38, wherein the rasping points of a surface 34 have been eliminated by means of a burnishing or polishing operation. A satisfactory burnishing operation comprises rolling a ball 34 between hardened flat surfaces until the rasping points are worked down to conform to a common spherical surface. The pits between the rasping points are, at the most, only slightly altered in

such a burnishing operation, and remain as indentations in the common spherical surface. Alternatively, the rasping points may be removed, or at least flattened sufficiently to avoid the deleterious wearing action above noted, by a final light polishing or lapping operation employing an abrasive which is substantially finer than that used in the abrading operation.

It is recognized, incidentally, that the prior art includes examples of balls having other than smooth, continuous spherical surfaces, but the surface discontinuities therein are produced by incision or, in some cases, by molding. It is not deemed possible, however, to obtain either the necessary close conformance to overall sphericity of the ball or the equally necessary fineness of abraded surface where these latter forming methods are used. In general, a pitted or "Indented surface" is preferable over one which contains a pattern of directionally continuous lines.

It is to be understood that the use of the expression "Indented surface" is not meant to be limiting, but to be descriptive of a surface generally similar to that obtainable in the abrading and burnishing process described hereinbefore. In other words, an indented surface as used here implies a surface having a multiplicity of microscopic abrasions of unpatterned direction, and especially such a surface wherein abradent projections have been removed, as by burnishing. Such a surface might, for example, be described as having a "satin finish"; it is not, on the other hand, producible by ordinary molding or by incision tooling, which involves specific removal of appreciable amounts of metal.

It is not meant to imply that the above-described process is the only way in which a satisfactorily roughened surface may be obtained. For example, a surface corroded by chemicals, as in etching, could be considered equivalent to the mechanically abraded surface described above, provided only that the same requirements for overall sphericity, fineness of surface texture, and absence of rasping peaks be met. Various tools, abrasives, etc., may be used in mechanical abrasion of the spherical surface and in subsequent burnishing of the same.

In use, it is evident from the foregoing description that a ball 36 provided with an indented surface 38 is mounted in the socket 16 of a tip 12, as is the ball 18 of Figure 1. The coefficient of friction between such a ball and even very smooth surfaces, such as glazed or oiled paper, is sufficient to cause the ball to rotate in its socket as the tip is moved over the paper. As a result, a continuous path of ink is transferred from the ball to the paper surface, as is well understood in the art.

Clearly, there has been provided a ball for ball point pens and a method for providing a roughened finish on the same which together fulfill the objects and advantages sought therefor.

It is to be understood that the foregoing description and the accompanying drawing have been given only by way of illustration and example. Neither is it to be construed in a limiting sense, and the scope of the invention is to be considered limited only by the claims which follow.

What is claimed is:

1. In a method of producing a ball for a ball point pen, the steps of finishing the ball to an intermediate smooth glossy spherical surface, roughening said surface to provide a multiplicity of crater-like indentations and peak-like projections, and subsequently flattening the tops of said peak-like projections to provide a cratered substantially spherical surface on said ball.

2. The method of claim 1 wherein said roughening step comprises subjecting said surface to the action of a corrosive chemical.

3. The method of claim 1 wherein said roughening step comprises subjecting said surface to mechanical abrasion.

4. The method of claim 1 wherein the step of flattening the tops of said peak-like projections is accomplished by a burnishing operation.

5. The method of claim 4 wherein said burnishing operation comprises rolling the ball between hard, polished surfaces.

6. The method of claim 1 wherein the step of flattening the tops of said peak-like projections is accomplished by a light polishing operation.

7. The method of claim 6 wherein said polishing operation comprises abrading top portions of said peaks with a relatively fine abrasive material.
